(57) **CLAIM**

I claim the ornamental design for a pry bar, as shown and described.

DESCRIPTION

FIG. 1 is an isometric view of a pry bar in accordance with the present invention.

FIG. 2 is an isometric view of the pry bar as shown in FIG. 1, but inverted.

FIG. 3 is a top side view of the pry bar shown in prior Figures.

FIG. 4 is a right side view of the pry bar shown in prior Figures.

FIG. 5 is a left side view of the pry bar shown in prior Figures.

FIG. 6 is a bottom side view of the pry bar shown in prior Figures.

FIG. 7 is an end view of the prying chisel end of the pry bar shown in prior Figures.

FIG. 8 is an end view of the prying hook end of the pry bar shown in prior Figures; and,

FIG. 9 is a cross section of FIG. 6 taken about line 9—9.
